UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

LINOTYPE-MACHINE.

No. 888,176.

Specification of Letters Patent.

Patented May 19, 1908.

Application filed March 6, 1908. Serial No. 419,547.

To all whom it may concern:

Be it known that I, DAVID S. KENNEDY, of borough of Brooklyn, county of Kings, and State of New York, have invented a new and useful Improvement in Linotype-Machines, of which the following is a specification.

This invention has reference to that class of line-casting machines in which the matrices are each provided with two characters, at different levels, and the assembling mechanism so constructed that it may be caused to present each matrix in a composed line at the upper or the lower level, to bring its upper or its lower character into use, as demanded, as illustrated, for example, in U. S. Letters Patent to Rogers, No. 615,909. In this mechanism the matrices are delivered one after another to the horizontal channel in the so-called "assembling elevator." This elevator is formed with horizontal shoulders which sustain the matrices at the lower, or normal, level, and is also provided, above these shoulders, with two horizontal retractable blades arranged end to end to sustain the matrices at the higher level when demanded.

At the receiving end the assembling channel is provided with fixed vertical lips to retain the lower ends of the incoming matrices. As heretofore constructed these lips were made of such height as to retain the matrices whether in the upper or the lower position. In practice it was found that these tall, thin lips were frequently bent out of shape, that they would sometimes interfere with matrices passing to the lower level, and that occasionally a thin matrix would assume an improper relation to the lip. To overcome this difficulty I divide the forward retaining lip horizontally into two sections, or provide two lips, one above the other, the upper lip, which retains the matrices in the upper position, being retractable, so that it may be thrown out of action when the matrices are to pass to the lower position. I prefer to attach the lip to the short rail by which the matrices are sustained in the upper position, but it may be independently mounted.

In the drawing I have shown my improvement applied to an assembler of the form shown in the above named Rogers patent, but it is to be understood that it may be applied to any assembling mechanism in which the matrices are delivered downward and lat-

erally one after another to the end of the line. Referring to the drawings, Figure 1 is a plan view of the receiving end of the assembling elevator with my improvement incorporated therein, the retaining lip being retracted to permit the free passage of the matrices to the lower level. Fig. 2 is a similar view with the lip advanced to its operative position. Fig. 3 is an end elevation of the parts shown in Fig. 1, looking in the direction of the arrow in the last-named figure. Fig. 4 is an end elevation looking in the direction of the arrow in Fig. 2. Fig. 5 is a front elevation of the parts shown in the preceding figures. Fig. 6 is a perspective view of the sliding rail with the lip attached and of the parts which are immediately associated therewith.

Referring to the drawings, I represent the assembling elevator into which the matrices are successively delivered at one end in a vertical position, the line thus formed being advanced horizontally step by step as the successive matrices are added. The parallel walls of this assembler, between which the matrices are received, are formed with horizontal shoulders, i^{20} to receive and sustain the lower ends of the matrices when they stand in the lower or normal position, as indicated by the dotted lines in Fig. 3.

At the front side the assembler contains two horizontal longitudinal slides, i^{10} and i^{11} , standing end to end, and so arranged that either or both may be projected inward to receive the incoming matrices and sustain them at the upper, or abnormal, level indicated by the dotted lines in Fig. 4. The slide i^{11} at the receiving end of the assembler is independently retractable, by means of a lever, i^{12} , so that certain matrices in a line may be permitted to pass to the lower level while others are sustained by the slide i^{10} at the upper level.

So far as described the foregoing parts are constructed and operated in the same manner as the parts indicated by like letters in the Rogers patent.

At the receiving end the assembler is provided with spring pawls, i^{21} , to engage and retain the upper ends of the entering matrices, and also provided with fixed vertical plates, i^{22} , to retain the lower ends of the matrices as they settle to their places in the assembler, so that they cannot escape therefrom. Heretofore the plate i^{22} at the front side of the assembler has been made of such

height that it would engage and hold the matrices not only at their lower, but also at their higher level.

In carrying my invention into effect I reduce the height of the front plate i^{22} , so that it will retain the matrices only when at the lower level; and as a substitute for the portion removed from the upper end of the plate I provide the lip or plate i^{23} , formed upon, or attached to, the inner end of the slide i^{11} . When this slide is moved rearward or inward in order to receive and sustain the matrices the lip is at the same time carried inward from the position shown in Figs. 1 and 3 to the position shown in Figs. 2 and 4, so that it will engage and hold the matrices standing at the upper level. When the slide i^{11} is withdrawn to permit the passage of the matrices to the lower level the lip i^{23} is carried with it out of the path of the matrices, so that the latter may pass to the lower level without interference.

The essence of my invention consists in providing a vertical lip or detaining device, i^{23} , adapted to hold the matrices when at the upper level in the assembler, and movable so that it may be thrown out of action, and out of the path of the matrices, when they are to pass to the lower level. It is to be understood that this lip may be varied in form and arrangement at will, provided only that it has the mode of action herein described.

In this class of machines the rails or devices which sustain the matrices at their upper level are made of various forms, and movable in various ways, well known to those familiar with the art, and it is to be understood that my movable lip may be applied to, or combined with, any one of these devices.

Matrices bearing two characters are commonly known in the art as "two letter matrices," and mechanisms for assembling these

matrices are generally known as "two-letter 45 assemblers."

Having described my invention, what I claim is:

1. In a channeled assembler for two letter matrices, controllable means for sustaining the matrices at different levels, and a device retractable at will for retaining side-wise within the assembler the lower ends of the matrices at the upper level. 50

2. A channeled assembler for two letter 55 matrices provided with controllable means for sustaining the matrices above the normal level, in combination with the vertical lip i^{23} , movable at will into and out of position for engaging the lower ends of the 60 matrices.

3. In an assembler for two letter matrices, means controllable at will for determining the height of the incoming matrices, said means provided with a vertical lip to retain 65 the matrices when assembled at the upper level.

4. The channeled assembler for two letter 70 matrices provided with the slide i^{10} and also with the slide i^{11} , the latter having a vertical lip, i^{23} .

5. The movable matrix support i^{11} , provided with a matrix retaining lip i^{23} substantially as shown.

6. In a channeled assembler for two letter 75 matrices the combination of controllable means for supporting the matrices above the normal level, a fixed plate, i^{22} , to retain the lower ends of the matrices in the assembler, and a retractable plate or lip, i^{23} , to engage 80 the matrices at the upper level only.

In testimony whereof I hereunto set my hand this 26 day of Feb., 1908, in the presence of two attesting witnesses.

DAVID S. KENNEDY.
